RATCHET MECHANISM

William H. Odlum, Wilmette, and Karl A. Paine, Park Ridge, Ill., assignors to Duro Metal Products Company, Chicago, Ill., a corporation of Illinois

Application November 8, 1944, Serial No. 562,464

8 Claims. (Cl. 192—43.2)

This invention relates to ratchet mechanisms, and particularly to those adapted to use for driving tools and the like.

It is a general object of this invention to provide an improved reversible ratchet mechanism which is compact, rugged and well adapted to use for driving tools such as wrench sockets, screw drivers, bits and the like.

Another and more specific object of the invention is to provide a reversible ratchet mechanism having pairs of pawls for operation in each direction which function alternately to provide twice as many driving positions for the mechanism as there are ratchet teeth, thus establishing small angular driving increments while maintaining the strength of coarser teeth.

The invention has for another object the provision of tooth angles on the pawls related in such a way to the normal direction of movement of the pawls and the direction of the driving force applied therethrough that the application of driving force results in a component of force urging the teeth of the ratchet and pawl into engagement.

It is also an object of the invention to provide a reversible ratchet mechanism having a direction control instrumentality protected against inadvertent operation.

Other objects and advantages of the invention will be apparent from the following description and the accompanying drawings in which similar characters of reference indicate similar parts throughout the several views.

Figure 1 is a perspective view of a tool adapted for use in driving wrench sockets and the like, and to which the ratchet mechanism of our invention is adapted;

Fig. 2 is a fragmentary bottom view of a portion of the tool shown in Fig. 1;

Fig. 3 is a fragmentary top view of a tool such as is shown in Fig. 1 and including a modification of a portion of the structure;

Fig. 4 is a fragmentary side sectional view showing a part of a preferred form of ratchet mechanism, made in accordance with our invention, and having the section taken substantially on a line 4—4 of Fig. 1;

Fig. 5 is a sectional plan view of a ratchet mechanism embodying a preferred form of our invention, in which the section is taken substantially on a line 5—5 of Fig. 4;

Figs. 6 and 7 are top plan views of the internal parts of our preferred form of ratchet mechanism showing two different operating positions of the mechanism;

Fig. 8 is an exploded view of the ratchet mechanism shown in Figs. 4 to 7, inclusive, illustrating the parts of the mechanism in an orderly disassembled relation;

5 Figs. 9 and 10 are enlarged top plan views of parts of the disclosed ratchet mechanism.

Although it is understood that the ratchet mechanism disclosed herein may be adapted to many uses and to other tools, it is in this instance disclosed in an exemplary association with a driving tool for wrench sockets and the like. In this adaptation, illustrated generally in Figs. 1, 2 and 3, a preferred form of the ratchet mechanism of our invention is disclosed in its association with a driving member 20 comprehending a lever arm 22 having at one end a head 23 which houses the ratchet mechanism, and at its other end a grip 24 to which manual driving force is applied for actuating a tool driving shank 25 in one direction or the other depending upon the angular position of a direction control knob 26. A spring urged detent 27 of well known construction is preferably provided in the tool driving shank 25 and projecting from one side thereof releasably to engage various driven tools such as wrench sockets.

Referring to the more detailed disclosure of the ratchet mechanism embodying our invention, as shown in Figs. 4 to 10, inclusive, the head 23 has 30 an annular opening 28, on the wall of which opening is a predetermined number of axially disposed internal ratchet teeth 29. The inner ends of the teeth are substantially flat or slightly concave, so that together they provide a bearing 35 rotatably supporting driven member 36. A retaining ring 30 is secured against a shoulder 32 in a counter-bore 33 at one end of the opening 28 by a rolled edge 34 at the end of the head 23. This retaining ring 30 has an opening 35 through which a shoulder portion 40 of the driven member 36 projects with a small clearance allowance around the surface 39 of the shoulder. A cylindrical body 37 comprises the part of the driven member 36 which is disposed within the opening 28 and has bearing engagement with the ends of the ratchet teeth 29. An end bearing surface 38 is provided by one end of the body 37. The bearing surface 38 on the driven member 36 co-acts with the adjacent plane surface of the retaining ring 30 to provide endwise support for the driven member.

40 Referring to Figs. 4 and 8, an axial cylindrical bore 42 in the end of the driven member 36 opposite the tool driving shank 25 rotatably supports a stud 43, which stud has a cylindrical body

44 at the outer end of which are axially disposed, in superimposed relation, a square shank 45, a circular extension 46 and a second square shank 47. The circular extension 46 passes through a circular opening 48 in a second retainer ring 49; the second retainer ring being secured in a counter-bore 50 in the end of the head 23 opposite the retainer ring 30 by rolled edge 52. Clearance is desirably provided between the extension 46 and the retainer ring 49 to avoid the possibility of turning the stud 43 during relative movement between the driving and driven members and to insure ease of separately rotating the stud.

Having reference to Figs. 5 and 8, parallel transverse slots 53 and 54 are provided in the end of the cylindrical body opposite the tool driving shank 25, and are preferably spaced equidistantly from opposite sides of the axial bore 42. The slots 53 and 54 are desirably rectangular in section and have beveled or filleted corners such as 55 and 56 for strengthening the structure. A pair 57 and 58 and another pair 59 and 60 of oppositely disposed pawls are slidably mounted in the slots 53 and 54; the oppositely disposed pair of pawls 57 and 58, respectively, having opposed longitudinal bores 62 and 63, and the pair of oppositely disposed pawls 59 and 60 have opposed longitudinal bores 64 and 65, respectively, which opposed bores retain the ends of compression springs 66 and 67. The oppositely disposed pairs of pawls in each of the slots 53 and 54 are biased apart and toward the ratchet teeth 29 by the springs 66 and 67.

The pawls 57 and 58, 59 and 60 are desirably paired diagonally for cooperative operation in controlling the driving of the driven member in either of the two directions. That is, diametrically opposed pawls, such as 57 and 60, in opposite ends of the different slots preferably control the actuation of the driven member in one direction; while the diagonally opposed pawls 58 and 59 control the actuation of the driven member in the opposite direction.

At their outer ends the pawls 57, 58, 59 and 60, respectively, have teeth 68, 69, 70 and 71 adapted to mesh with the ratchet teeth 29; the teeth 68 and 70 of the pawls 57 and 59 being similar, and the teeth 69 and 71 of the pawls 58 and 60 being similar. In order to decrease the increments of movement of the driving member which are necessary to pass from one driving position to the next without increasing the number of ratchet teeth, the teeth, such as 63 and 71, of the diametrically opposed operating pairs of pawls are differently positioned on the pawls so as alternately to mesh fully for driving action with the ratchet teeth. Desirably, the teeth of one of the pawls, such as 57, of one of the operating pairs, such as 57 and 60, fully mesh with the ratchet teeth at half the distance of movement necessary for the teeth of the other pawl, such as 60, to pass between successive ratchet teeth. This relation of the teeth of the diametrically opposed operating pairs of pawls permits the use of heavier and consequently stronger ratchet teeth, while providing twice as many operative driving positions of the driving member relative to the driven member as there are ratchet teeth.

The difference in the teeth on the pawls is illustrated by comparison of the large plan views of Figs. 9 and 10. In these views, also, certain angular relations of the tooth faces are disclosed. Faces 72 of the teeth 70 on the pawl 59 (Fig. 9) are the driving or force-carrying faces; while on

the teeth 71 of the pawl 60 (Fig. 10), the faces 73 are the driving or force-carrying faces. Faces 74 and 75 of the teeth 70 and 71, respectively, are pawl-moving or camming faces. It is to be understood that the relations of the teeth and surfaces of the pawls 57 and 58 are similar. The co-acting ratchet teeth are desirably symmetrical to provide like operating characteristics in both directions. Also, the pawl teeth are preferably fully engaged when in mesh with the ratchet teeth for driving the driven member.

In addition to the details of the relations of the pawl and ratchet teeth which have been discussed, it is pertinent to note that, as is illustrated in Figs. 9 and 10, the driving faces 72 and 73 of the pawl teeth are angularly disposed so as to vary from parallelism with the side faces of the pawls in such a direction that the transmission of driving force through the driving faces creates a resultant component of force tending to urge the pawl teeth into engagement with the ratchet teeth. In other words, the driving faces 72 of the pawl 59 vary from parallelism from the side faces 76 and 77 of the pawl in amounts indicated by angles α and β . The resultant summation and direction of the transmitted components of force is such that the pawl is urged longitudinally of the sides 76 and 77 toward the ratchet teeth. The same is true of the pawls, such as 60, wherein the driving faces 73 of the pawl teeth vary from parallelism with the side faces 78 and 79 by angles c and d .

To accomplish changes of the direction of operation of the disclosed ratchet mechanism, a retainer plate 80 (Figs. 4, 6, 7 and 8) having diametrically opposed peripheral slots 82 and 83 and a square central opening 84 is carried by the square shank 45 on the stud 43 adjacent the end of the driven member for rotation with the stud 43 relative to the ring 49 and driven member 36. The ends of the slot 82 are adapted to engage pins 85 and 86 which project outwardly from the top surfaces of the opposed pawls 57 and 58 in the slot 53. Likewise, the ends of the slot 83 are adapted to engage pins 87 and 88 which project outwardly from the top surfaces of the opposed pawls 59 and 60. The lengths of the slots 82 and 83 are preferably such that in a neutral position all four of the pawls 57 and 58, 59 and 60 are held out of engagement with the ratchet teeth 29. However, in operation the retainer plate 80 engages the pins of diametrically opposed operating pairs of pawls to render those pawls inoperative; while the other diametrically opposed operating pair of pawls is free to engage the ratchet teeth. The inoperative pawls, in each instance, serve as substantially stationary anchors for the ends of the compression springs 66 and 67, which spring bias the operative pawls toward the ratchet teeth.

As shown in Fig. 6, the pawls 57 and 60 are held in an inoperative position away from the ratchet teeth 29 by the retainer plate 80. In this position, and as viewed in the drawing, the driving force is transmitted through the pawls 58 and 59, which pawls are alternately effective to drive the driven member 36 in a clockwise direction. Force applied to the driving member in the clockwise direction is transmitted through the driving faces of the pawl teeth 70 and 71. Rotation of the driving member in the opposite direction cams the respective pawls inwardly against the biasing forces of the springs 66 and 67 to cause the ratchet teeth 29 to pass over the surfaces of the pawl teeth.

When the retainer plate 80 is in the position shown in Fig. 7, the pawls 58 and 59 are held in an inoperative position away from the ratchet teeth 29 and the pawls 57 and 60 are biased by the springs 66 and 67 into engagement with the ratchet teeth. In this position, and as viewed in the drawing, the ratchet mechanism is operative to transmit driving force from the driving to the driven member in a counter-clockwise direction.

In order to hold the retainer plate 80 in the operating position, illustrated in Figs. 6 and 7, the stud 43 has angularly disposed plane intersecting surfaces 90 and 92 (Figs. 4 and 5) cut into the surface of the cylindrical body portion thereof in predetermined angular relation with respect to the square shank 45 which carries the retainer plate. A ball detent 93 is longitudinally movable in a radial bore 94 in the body portion 37 of the driven member and biased toward engagement with the plane surfaces 90 and 92 by a compression spring 95. One end of the compression spring 95 engages the ball detent, while the other end is retained in the bore 94 by an axially disposed pin 96.

Mounted on the second square shank 47 for controlling the angular position of the stud 43, and consequently the position of the retainer plate 80, is the direction control knob 26; the knob being secured in position by a screw 97 or other suitable means. Rotation of the direction control knob 26 turns the stud 43 to positions such that one or the other of the plane surfaces 90 or 92 is engaged by the ball detent 93. The action of the ball detent holds the stud in the position to which it is operated and hold the retainer plate in one or the other of the positions shown in Figs. 6 and 7 to control the direction of operation of the ratchet mechanism. In either of these positions the pins 85, 86, 87 and 88, whichever pair is engaged by the retainer plate, act to limit the rotation of the retainer plate and stud.

In the modification illustrated in Fig. 3, the retainer ring 49 is provided on its outer surface with an outwardly projecting circular flange 98 surrounding a direction control knob 99 and extending to a height above the surface of the control knob. This flange 98 protects the control knob 99 from accidental or inadvertent operation while permitting the user of the tool to rest one hand on the outer surface of the flange during the use of the wrench.

From the foregoing description it may be understood that we have provided an improved reversible ratchet mechanism adapted to uses such as the use in driving tools. The mechanism is easily controlled to determine the direction of operation by the manual actuation of the control knob. When desired the control knob may be protected from any accidental or inadvertent operation by a surrounding flange such as that shown in Fig. 3. The ruggedness of the driving parts of the ratchet mechanism is maintained without sacrificing the advantages of small operating increments by the use of pairs of alternately effective operating pawls for each direction of operation.

In addition to the foregoing advantages of our ratchet mechanism, the positions of the pawls and their respective directions of movement, as well as the positions of the pawl teeth, are so selected that the application of driving force to the driving member results in a component of force effective upon the driving pawl tending to

hold that pawl in close engagement with the ratchet teeth.

While we have illustrated a preferred embodiment of our invention, many modifications may be made without departing from the spirit of the invention, and we do not wish to be limited to the precise details of construction set forth, but desire to avail ourselves of all changes within the scope of the appended claims.

Having thus described our invention, what we claim as new and desire to secure by Letters Patent of the United States is:

1. A ratchet mechanism comprising, in combination, a driving member including a head having an annular opening and a predetermined number of internally disposed ratchet teeth facing said opening, a driven member having a cylindrical body rotatably supported in said opening and a projecting tool driving shank, said body having in the end thereof opposite said shank a pair of parallel transverse slots substantially equidistantly spaced on each side of the central axis of the cylindrical body, pairs of oppositely disposed pawls slidably mounted in said slots and having teeth adapted to engage said ratchet teeth, compression springs between said pairs of pawls biasing the pawls toward the ratchet teeth, the diagonally disposed pawls in different slots each being adapted to prevent rotation between the driving and driven members in one direction upon engagement with the ratchet teeth, the teeth of said diagonally disposed pawls being so positioned that they are alternately effective to prevent rotation between the driving and driven members in said one direction whereby the number of driving positions of the driving member relative to the driven member for each direction of rotation is twice the number of teeth, and means including a retainer plate for selectively holding diagonally disposed pawls in inoperative positions to determine the direction of operation of the ratchet mechanism.

2. A ratchet mechanism comprising, in combination, a driving member including a head having an annular opening and internally disposed ratchet teeth, a driven member having a cylindrical body rotatably supported in said opening and a tool driving shank, said body also having in one end thereof a pair of similar parallel slots, two oppositely disposed pawls slidably mounted in each of the slots, said pawls each being adapted to engage said ratchet teeth to prevent rotation between the driving and driven members in one direction and being alternately arranged so that the pawls in each slot are adapted to prevent rotation between the driving and driven members in both directions, the alternate pawls being so related to the ratchet teeth that they are alternately effective to prevent rotation between the driving and driven members in one direction thereby to provide two ratchet steps for each ratchet tooth, means for biasing the pawls toward the ratchet teeth, and means for selectively holding alternately disposed pawls in inoperative positions to determine the direction of operation of the ratchet mechanism.

3. A ratchet mechanism comprising, in combination, a driving member including a head having an annular opening and internally disposed ratchet teeth, a driven member having a cylindrical body rotatably supported in said opening and a tool driving shank, said body also having in one end thereof a pair of slots, two oppositely disposed pawls slidably mounted in each of the slots, said pawls each being adapt-

ed to engage said ratchet teeth to prevent rotation between the driving and driven members in one direction and being alternately arranged, the alternate pawls being so related to the ratchet teeth that they alternately engage said teeth thereby to provide two ratchet steps for each ratchet tooth, means for biasing the pawls toward the ratchet teeth, and means for selectively holding alternately disposed pawls in inoperative positions to determine the direction of operation of the ratchet mechanism.

4. A ratchet mechanism comprising, in combination, a driving member including a head having an annular opening and internally disposed ratchet teeth, a driven member having a cylindrical body rotatably supported in said opening and a tool driving shank, said body also having in one end thereof a pair of slots, two oppositely disposed pawls slidably mounted in each of the slots, resilient means disposed between two pawls in each slot for biasing the pawls toward the ratchet teeth, said pawls each being adapted to engage said ratchet teeth to prevent rotation between the driving and driven members in one direction, the pawls for preventing rotation between the driving and driven members in one direction being alternately arranged circumferentially of the cylindrical body with those for preventing relative rotation of the driving and driven members in the opposite direction, and means for selectively holding alternately disposed pawls in inoperative positions to determine the direction of operation of the ratchet mechanism.

5. A ratchet mechanism comprising, in combination, a driving member including a head having an annular opening and internal ratchet teeth, a driven member having a cylindrical body rotatably supported in said opening, said body having a cylindrical opening in one end and slots in said end on opposite sides of the opening, pairs of pawls slidable in each of said slots, said pawls each being adapted to engage said ratchet teeth to prevent rotation between the driving and the driven members in one direction, a part of said pawls preventing said rotation in one direction and a part in the other, means biasing said pawls toward engagement with said ratchet teeth, a stud rotatably supported in said cylindrical opening, detent means for releasably holding said stud in either of two angularly different positions, a retainer plate carried by said stud for rotation therewith, and means for providing lost motion connections between said retainer plate and selected ones of said pawls in each of the two positions of said stud to hold said selected ones of the pawls in inoperative positions in each of said stud positions, thereby to determine the direction of operation of the ratchet mechanism.

6. A ratchet mechanism comprising, in combination, a driving member including a head having an annular opening and internal ratchet teeth, a driven member having a cylindrical body rotatably supported in said opening, said body having a cylindrical opening in one end and slots in said end on opposite sides of the opening, pairs of pawls slidable in each of said slots, said pawls each being adapted to engage said ratchet teeth to prevent rotation between the driving and driven members in one direction, a part of said

pawls preventing said rotation in one direction and a part in the other, means biasing said pawls toward engagement with said ratchet teeth, a stud rotatably supported in said cylindrical opening, detent means for releasably holding said stud in either of two angularly different positions, a retainer plate carried by said stud for rotation therewith, means providing lost motion connections between said retainer plate and selected ones of said pawls in each of the two positions of said stud to hold said selected ones of the pawls in inoperative positions in each of said stud positions, thereby to determine the direction of operation of the ratchet mechanism, a manually operable knob means secured to the stud for turning the stud to said positions, and guard means surrounding said knob means to prevent inadvertent turning thereof.

7. A ratchet mechanism comprising, in combination, relatively rotatable driving and driven members, one within the other, one of said members having ratchet teeth thereon and the other carrying pairs of pawls, each of which pawls is linearly movable and adapted to engage the ratchet teeth to prevent the relative movement between said members in one direction, one of said pairs of pawls being adapted to prevent said relative movement in one direction and the other of said pairs preventing relative movement in the other direction, means biasing the pawls toward engagement with the ratchet teeth, the pawls of each pair being so related to each other and to the ratchet teeth that they are alternately engageable with the ratchet teeth at separate relative angular positions of said members to provide twice as many positions of engagement in each direction of relative movement as there are ratchet teeth, and manually operable means for selectively rendering said pairs of pawls inoperative to determine the direction of operation of the ratchet mechanism.

8. A ratchet mechanism comprising, in combination, a driving member including a head having an annular opening and internally disposed ratchet teeth, a driven member having a cylindrical body rotatably supported in said opening, said body having in one end thereof a pair of parallel slots, two oppositely disposed pawls slidably mounted for linear movement in each of said slots, said pawls each including a toothed end having angularly disposed tooth surfaces adapted to engage said ratchet teeth to prevent relative rotation between the driving and driven members in one direction, said pawls being divided into pairs and each pair being adapted to prevent relative rotation of the members in one of the two directions of relative rotation, said angularly disposed tooth surfaces of each pawl being so related angularly to the direction of linear movement of the pawl and the surfaces of the ratchet teeth engaged thereby that torque applied to the head of the driving member effects a resultant component of force on the engaged pawl tooth urging the pawl toward the ratchet teeth, resilient means normally biasing the pawls toward the ratchet teeth and means for rendering pre-selected pairs of said pawls inoperative to determine the direction of operation of the ratchet mechanism.
